UNITED STATES PATENT OFFICE.

HERBERT M. DAWLEY, OF BUFFALO, NEW YORK, ASSIGNOR TO THE PIERCE-ARROW MOTOR CAR COMPANY, OF BUFFALO, NEW YORK.

DESIGN FOR A HEADLIGHT.

44,606.

Specification for Design.

Patented Sept. 2, 1913.

Application filed May 31, 1911. Serial No. 630,490. Term of patent 14 years.

● *To all whom it may concern:*

Be it known that I, HERBERT M. DAWLEY, a citizen of the United States, residing at Buffalo, in the county of Erie and State of New York, have invented a new, original, and ornamental Design for Headlights, of which the following is a specification.

The accompanying drawing represents in Figure 1 a perspective view, in Fig. 2 a rear elevation and in Fig. 3 a side elevation of a headlight embodying the design.

The following are the characteristic features of the design: The body of the headlight is of polygonal shape in cross section

and substantially bell-shaped in contour the faces thereof being of compound curvature lengthwise of the body. The flaring front end of the body joins a circular lens rim having flat faces meeting at an angle, and the small rear end of the body is externally convexed.

I claim:

The ornamental design for a headlight, as shown and described.

HERBERT M. DAWLEY.
